FRICTION DRAFT GEAR FOR RAILWAY CARS

William A. Geiger, Chicago, Ill., assignor to William P. Sidley, M. F. Back, Albert P. Withall, Edwin C. Austin, and George A. Johnson, all of Chicago, Ill., and Alice T. Miner, Chazy, N. Y., as trustees of The William H. Miner Foundation

Application January 28, 1944, Serial No. 520,034

5 Claims. (Cl. 213—35)

This invention relates to improvements in draft gears for railway cars.

One of the objects of the invention is to provide a railway draft gear embodying the friction shock absorbing mechanism especially designed for absorbing the shocks produced by a pulling or draft action applied to the coupler or drawbar of a railway car.

A more specific object of the invention is to provide a draft rigging for railway cars comprising a drawbar and a friction shock absorbing mechanism especially designed to cushion the pulling shocks transmitted to the drawbar, wherein the friction shock absorbing mechanism includes a tapered friction post, pivotally mounted friction shoes slideable along said post in frictional engagement therewith, and a spring resistance means acting upon said shoes to force them into frictional engagement with the post and thereby frictionally oppose the movement of the shoes as the draft or pull is developed in the coupler, and wherein the pull upon the coupler is applied to the shoes through the fulcrums or pivotal mountings of the shoes, thus providing high combined spring and frictional resistance to provide the desired cushioning action.

Other objects of my invention will appear from the following description and claims in connection with the accompanying drawing which illustrates one embodiment of the invention.

Referring to the accompanying drawing,

Fig. 1 is a longitudinal sectional view through the underframe structure of a railway car, at one end thereof, illustrating my improvements in connection therewith;

Fig. 2 is an inner end elevational view on an enlarged scale, of the structure shown in Fig. 1, the underframe structure of the car being omitted;

Fig. 3 is a vertical sectional view substantially on the line 3—3 of Fig. 2, with certain parts shown in elevation;

Fig. 4 is a transverse sectional view on the line 4—4 of Fig. 3; and

Figs. 5 and 6 are inner end views of the friction shoes and illustrating the segmental platforms which form seats for the spring resistance means.

Referring more particularly to Fig. 1, 1 indicates the usual end sill of the car underframe structure, and 2 indicates one of the center sills. The usual car underframe structure comprises two spaced center sills 2 which are fixed at their front ends to the end sill 1 and extend rearwardly or inwardly of the end sill. The underframe

structure has a transverse connecting member 3 which extends between the two sills and has its opposite ends secured by rivets or otherwise to said sill members. This transverse member 3 serves as the front stop of the draft rigging of the car and is provided with a central opening 4 through which the shank of the drawbar extends. The end sill 1 and the transverse stop member 3 are of channel-shaped cross section and are connected by the top and bottom plates 14 which are secured to the top and bottom flanges of said channel members.

The drawbar A of the draft rigging has an enlarged head 5 at its outer end, and this head has the usual coupler hook 6 formed thereon. The shank 8 of the drawbar A, which extends rearwardly from the head, is of cylindrical cross section, that is, in the form of a cylindrical bar or shaft, and carries the usual nut 9 which is threaded on the rear or inner end of the shank. The drawbar A is accommodated for lengthwise sliding movement in the aligned openings 10 and 4 in the end sill member 1 and the transverse connecting member 3, respectively. The head 5 of the drawbar is reduced in size at the end where it joins the shank 8, thereby providing top and bottom shoulders 11 adapted to engage the front face of the end sill 1 to limit the inner movement of the drawbar.

My improvements, as shown in the drawing, comprise in general a central friction post B, friction shoes C, a fulcrum bearing D for the shoes, and a spring resistance means E, through all of which members the shank 8 of the drawbar extends.

The shock absorbing unit includes the central friction post B which is hexagonal in section and has a longitudinal bore 12 through which the drawbar shank extends and in which it is freely movable. The post has, at its outer end, a lateral flange 13 which is preferably circular in shape and which is seated against the transverse stop member 3 of the frame. The adjacent two faces 14 on opposite sides of the post provide friction faces in V-shaped or angular relation, and the post is tapered rearwardly so that these friction faces are accordingly tapered. These tapered friction faces are adapted to be frictionally engaged by the longitudinally movable shoes C which are disposed on opposite sides of the post and are provided with friction faces 15 in V-shaped or angular relation so as to be complementary to the friction faces 14 of the post. Each friction shoe has associated with it a segmental shaped flange or platform member 16

which is disposed substantially at right angles to the length of the shoe and which is connected with its respective shoe by the arms 17 which are spaced apart to provide for the drawbar shank. The arms 17 are extended laterally so that the platform of each shoe is disposed on the opposite side of the post to that on which the shoe is disposed. As shown more clearly in Figs. 5 and 6, the arms 17 of the one shoe are spaced apart farther than those of the other shoe. Each of the arms 17 of both shoes have rounded lugs 18 projecting beyond the plane of the under face of the platform members and all arranged in transverse alignment. These fulcrum lugs are seated in the channels 19 of the bearing plate D to provide pivots or fulcrums for the shoes, whereby the shoes can swing toward and from the friction post. The bearing plate D has a central opening 20 through which the drawbar shank extends and is seated against the nut 9 on the shank, whereby the draft or pull upon the drawbar is applied to the shoes through this bearing plate and the fulcrums of the shoes.

The spring resistance in the present structure is comprised of outer and inner coil springs 21 and 22 concentrically arranged, and positioned between the flange 13 of the post and the segmental platforms or members 16 of the shoes. The inner spring 22 is relatively lighter than the outer coil 21, but the ends of both springs bear against the flange 13 and segments 16.

The assembly of the structure is a very simple matter. After the shank of the drawbar is inserted through the end sill 1 and the transverse plate 3 until the shoulders 11 engage the end sill, the central friction post B is inserted over the end of the shank until the flange 13 bears against the transverse stop 3. After the inner and outer spring coils are centered around the post, the shoes are inserted through the ends of the springs until the shoes engage the friction post, the bearing member D is put in place on the shank and against the fulcrum lugs of the shoes, and the nut 9 is threaded onto the shank and is drawn up sufficiently to place the springs under an initial compression. A cotter pin 23 is inserted through a suitable hole in the end of the drawbar shank to prevent the accidental displacement of the nut.

In operation it will be seen that a draft shock or pull on the drawbar is applied through the nut 9 to the bearing plate D and thence through the fulcrums of the shoes to the segmental platforms 16 to the springs which cushion the shock. In addition, the pressure of the springs on the platforms swings the shoes into tight frictional engagement with the tapered friction post. Thus the high shock absorbing capacity, both of the springs and the snubbing action of the friction shoes, is attained. When the actuating force is reduced, the springs restore all of the parts to normal position, the inward movement of the drawbar being positively limited by the stops 11.

I have herein shown and described what I now consider the preferred manner of carrying out the invention. It will be understood that changes may be made in the construction, operation and arrangement of the various parts, without departing from the spirit of the invention, and it is understood that I contemplate such changes as fairly fall within the scope of the appended claims.

I claim:

1. In a railway draft rigging for a railway car having a front stop, the combination of a tapered friction post bearing against said front stop, a pair of pivoted shoes frictionally engaging said

post and movable lengthwise thereof, seat members connected with said shoes, spring resistance means interposed between said front stop and said seat members, a pivot bearing member for said shoes, and a drawbar extending longitudinally through said post, springs and pivoted shoe members and connected to said bearing member for transmitting the pull of the drawbar to the pivots of said shoes.

2. In a railway draft rigging for a railway car having a front stop, a coupler having a drawbar shank extending lengthwise of the car, and shock absorbing mechanism interposed between the drawbar and the front stop comprising a hollow, tapered post through which said drawbar shank extends, having a flanged outer end bearing against said front stop, said post having tapered frictional surfaces on its exterior, a fulcrum bearing member carried by the shank, a pair of friction shoes engaging the friction faces of the post and movable lengthwise thereof, said shoes being fulcrumed on said bearing member and having laterally extending members forming spring seats, and coil spring means interposed between said post flange and said seats.

3. In a railway draft rigging for a railway car having a front end sill and a front stop spaced inwardly therefrom, a coupler drawbar slidably mounted in said end sill and front stop, and extending inwardly beyond said front stop, a tapered friction post having a flange at its outer end bearing against said front stop and having a longitudinal bore through which the drawbar extends, a pair of friction shoes longitudinally movable with respect to the post and disposed on opposite sides of the post and having friction surfaces engaging the post, a bearing member on said drawbar adapted to be moved thereby upon a draft pull on said drawbar, fulcrum members for said shoes bearing against said bearing member, lateral extensions for said shoes, and a pair of concentrically arranged coil springs enclosing said post and friction shoes, and bearing upon said post flange and said extensions.

4. In a railway draft rigging for a railway car, the combination of an end sill, a drawbar slidably mounted in said end sill, having coupling means at its forward end and adapted to be subjected to draft shocks, a stop member in the frame structure of the car through which said drawbar extends, a hollow post through which the drawbar extends lengthwise beyond the rear end thereof, a head on said post bearing against said stop member, said post being exteriorly tapered and hexagonal in cross section to provide pairs of angularly related frictional surfaces on opposite sides thereof, a pair of shoes movable lengthwise of said post and having angularly related friction surfaces in frictional engagement with the surfaces of said post, a bearing member on said drawbar, means forming fulcrums for said shoes on said bearing member disposed in transverse alignment, coil spring resistance means surrounding the post and shoes and bearing at its front end against said head, and arms on said shoes bearing against the other end of said spring resistance means to force the shoes against the post and frictionally resist the lengthwise movement of the shoes in response to the pull on the drawbar.

5. In a railway draft rigging for a railway car, the combination of an end sill, a drawbar slidably mounted in said end sill, having coupling means at its forward end and adapted to be subjected to draft shocks, a stop member in the

frame structure of the car through which said drawbar extends, a hollow post through which the drawbar extends lengthwise beyond the rear end thereof, a head on said post bearing against said stop member, said post being exteriorly tapered and hexagonal in cross section to provide pairs of angularly related frictional surfaces on opposite sides thereof, a pair of shoes movable lengthwise of said post and having angularly related friction surfaces in frictional engagement with the surfaces of said post, a bearing member on said drawbar, means forming fulcrums for said shoes seated on said bearing member and dis-

posed in transverse alignment in the longitudinal axis of said post, concentrically disposed coil springs surrounding the post and shoes and bearing at their front ends against said head, and 5 segmental-shaped platform members connected with the shoes and disposed at the side of the post opposite that of the shoes with which they are connected, said platform members bearing against the other ends of said springs and adapted 10 upon the pull of the drawbar to force the shoes against the post to resist the lengthwise movement of the shoes.

WILLIAM A. GEIGER.
